UNITED STATES PATENT OFFICE.

CHARLES M. RICHARDSON, OF WASHINGTON, DISTRICT OF COLUMBIA.

MAIL-DISTRIBUTING DEVICE.

1,391,693.

Specification of Letters Patent. Patented Sept. 27, 1921.

Application filed March 14, 1919. Serial No. 282,625.

To all whom it may concern:

Be it known that I, CHARLES M. RICHARDSON, a citizen of the United States, residing at Washington, in the District of Columbia, 5 have invented certain new and useful Improvements in Mail-Distributing Devices, of which the following is a specification.

My invention relates to mail distributing devices.

10 It is my purpose to provide a device of this character through the instrumentality of which the rapidity of distribution of mail can be greatly increased and which will correspondingly increase the amount of mail 15 matter that can be distributed by each individual clerk whereby economy of operation is had both in respect to output and the amount of labor required.

Furthermore, it is my purpose to provide 20 a device of this character which will occupy a relatively small space, and which can be constructed to accommodate an indefinite number of clerks.

It is also my purpose to provide a device 25 of this character which will be positive and efficient in operation and which will distribute letters in edge supported stacks, that is, each letter resting upon one of its edges and the letters of the stack being arranged 30 side to side whereby they may be conveniently removed and bound up for transportation.

I will describe my invention in the best 35 form known to me at present, but it will be understood that it is susceptible to extensive changes in forms and proportions and to desirable additions with the exercise of only ordinary mechanical skill and without departing from the spirit thereof.

40 In describing my invention in detail reference will be had to the accompanying drawings wherein like characters of reference denote corresponding parts in the several views, and in which—

45 Figure 1 is a plan view of my distributing device;

Fig. 2, a section on the line 2—2 of Fig. 1;

Fig. 3, a section on the line 3—3 of Fig. 1;

Fig. 4, a front elevation of the device;

50 Fig. 5, a view in elevation of one of the deflecting members for shifting the letters from the endless conveyer to a related spiral conveyer.

Fig. 6, a section on the line 6—6 of Fig. 5;

55 Fig. 7, a perspective view of one of the spiral conveyers;

Fig. 8, a plan view of a fragment of the device showing a modified and preferred form of spiral conveyer;

Fig. 9, a section on the line 9—9 of Fig. 60 8; and

Fig. 10, a section on the line 10—10 of Fig. 8.

Referring to the drawings my improved distributing device is shown as comprising 65 a table A which is provided with a plurality of receiving troughs 15, 16, 17 and 18 formed by vertical longitudinal walls 19, 20, 21, 22 and 23, said walls being connected at one end by a transverse wall 24. The 70 table A is further provided with a plurality of distributing troughs 25, 26, 27 and 28 which are disposed at right angles to and communicate with the troughs 15, 16, 17 and 18 respectively at the delivery ends of the 75 latter. It will be noted that the walls 19, 20, 21, 22 and 23 of the receiving troughs increase in height successively so that a suitable designation may be visibly applied to indicate to the distributor what letters are 80 to be deposited in each receiving trough. The bottoms of the receiving troughs are formed of endless conveyers 29, 30, 31 and 32 respectively. These conveyers are of multiple sprocket construction although any 85 other desirable construction may be utilized and are supported at their receiving ends upon sprocket wheels 33 fixed upon a drive shaft 34 suitably journaled on the table A and driven from any suitable source of 90 power (not shown). The conveyers 29 and 32 are of equal length and supported at their delivery ends upon sprocket wheels fixed on a shaft 35 suitably journaled on the table A and disposed directly beneath the common longitudinal center of the distributing troughs 25 and 28. Likewise the conveyers 30 and 31 are of equal length and are supported at their delivery ends upon sprocket wheels fixed on a shaft 36 suitably 95 journaled on the table A and disposed directly beneath the common longitudinal center of the distributing troughs 26 and 27. Mounted on the shaft 35 are spiral conveyers 37 and 38 which project through 100 openings 39 and 40 respectively in the bottoms of the troughs 25 and 28. Likewise spiral conveyers 41 and 42 are mounted on the shaft 36 and project through openings 105 43 and 44 respectively in the bottoms of the distributing troughs 26 and 27. In order to 110 shift the letters from the endless conveyers

to their related spiral conveyers I provide deflector plates 45 corresponding in number to the number of endless conveyers and also to the number of spiral conveyers. The deflector plate 45 associated with the endless conveyer 29 is mounted on the wall 20 while that associated with the endless conveyer 32 is mounted on the wall 22. The deflector plates associated with the conveyers 30 and 31 are mounted on opposite sides of the wall 21. Each deflector plate 45 comprises a base portion 46 adjustably mounted in a recess 47 formed in the related supporting wall. The active portion of each deflector plate extends diagonally across the related endless conveyer and serves to shift the moving letter into position to be operatively engaged by the related spiral conveyer. By referring to Fig. 7 it will be seen that I provide each of these spiral conveyers with two engaging lips 48 and 49 whereby it is rendered possible for the conveyer to operatively engage two letters during each complete revolution of the conveyer. In order to maintain letters in substantially the vertical position in which they are delivered from the spiral conveyers I dispose in each distributing trough a shiftable stacker block 50 against which the first letters are delivered and which are pushed outwardly by the accumulating stacks of letters as will be obvious. When a stack of letters is removed from a given distributing trough the related stacker block is of course manually returned to its initial position. It will be understood however, that any other suitable means may be employed for forming the letters delivered from the spiral conveyers into edge supporting stacks. Along the front of the table I have provided a plurality of extensions 51 which constitute a support for the supply of letters to be distributed while beneath each extension I suspend a seat 52 for the use of a distributor while at work.

While I have illustrated and described a distributing device embodying four receiving troughs and four distributing troughs the number of these troughs may be indefinitely increased to meet the requirements of any particular distribution and likewise the lengths of the receiving troughs may be indefinitely increased to accommodate any desired number of distributors.

In the operation of the device if a letter is deposited in the trough 18 it will be supported in substantially vertical position by the conveyer 32 and moved by the latter in the direction of the distributing trough 28.

When the letter reaches a point adjacent the delivery end of the conveyer it will be deflected outwardly by the plate 45 and positioned by the latter so as to be operatively engaged by the spiral conveyer 38 when it will be moved by said spiral conveyer in

substantially vertical position outwardly of the trough 28 and finally delivered against the stacker block 50. A corresponding operation will take place in respect to letters deposited in any of the other receiving troughs.

In Figs. 8, 9 and 10 I illustrate a preferred form of spiral conveyer for utilization in conjunction with the distributing troughs and in this form I construct said conveyers each of a strand of resilient material 53 which is adapted to yield in response to letters of varying thicknesses. In other respects the form of invention illustrated in Figs. 8, 9 and 10 is the same as that heretofore described.

I claim:

1. In a mail distributing device, a horizontal endless conveyer for initially receiving and moving letters thereon with the plane of each letter extending substantially in the direction of movement of the conveyer and intersecting the latter at an angle, a second conveyer for subsequently receiving and moving letters with the plane of each letter extending at right angles to the direction of movement imparted to the letters by said second conveyer, and means for shifting letters from the first conveyer to the second conveyer.

2. In a mail distributing device, an endless conveyer for initially receiving and moving letters, a spiral conveyer for subsequently moving letters in substantially vertical position, and means for delivering letters from the endless conveyer to the spiral conveyer.

3. In a mail distributing device, an endless conveyer for initially receiving and moving letters, a lateral trough at one end of the conveyer, a spiral conveyer operating in said trough for subsequently moving letters in substantially vertical position, and means for shifting letters from the endless conveyer into position to be operatively engaged by the spiral conveyer.

4. In a mail distributing device, a conveyer for initially receiving and moving letters, a spiral conveyer for subsequently moving letters in substantially vertical position and actuated by the first conveyer and means for shifting letters from the first conveyer into position to be operatively engaged by the spiral conveyer.

5. In a mail distributing device, a conveyer for initially receiving and moving letters, a spiral conveyer for subsequently moving letters in substantially vertical position, said spiral conveyer being formed of a strand resilient material whereby its coils are yieldable in response to letters of varying thicknesses, and means for shifting letters from the first conveyer to a position to be operatively engaged by the spiral conveyer.

6. In a mail distributing device, a plurality of conveyers for initially receiving and moving letters, a plurality of spiral conveyers associated with the first conveyers respectively for subsequently moving letters in substantially vertical position, and means for shifting letters from each first conveyer to a position to be operatively engaged by the related spiral conveyer.
- 10 7. In a mail distributing device, a plurality of endless conveyers for initially receiving and moving letters, a lateral trough at the end of each conveyer, a spiral conveyer operating in each trough for subsequently moving letters in substantially vertical position, and means for shifting letters from each endless conveyer to a position to be operatively engaged by the related spiral conveyer.
- 15 8. In a mail distributing device, a plurality of endless conveyers for initially receiving and moving letters, a lateral trough at the end of each conveyer, a spiral conveyer operating in each trough for subsequently moving letters in substantially vertical position, means for shifting letters from each endless conveyer to a position to be operatively engaged by its related spiral conveyer, and connections between
- 20 25 30 said endless and spiral conveyers whereby the operation of the former will actuate the latter.
9. In a mail distributing device, a plurality of contiguous endless conveyers for initially receiving and moving letters, said conveyers being arranged in pairs of equal length, a single rotatable shaft supporting the delivery ends of the conveyer of each pair, a pair of spiral conveyers mounted on each shaft to receive letters from respective endless conveyers of the corresponding pair and move same in substantially vertical position, and means for shifting letters from each endless conveyer to a position to be operatively engaged by the related spiral conveyer.
10. In a mail distributing device, a plurality of receiving troughs, a plurality of distributing troughs communicating respectively with the receiving troughs, means associated with each receiving trough for moving letters deposited therein to the related distributing trough, means associated with each distributing trough for further moving letters delivered from the related receiving trough in substantially vertical position, and means for supporting letters delivered from the moving means of each distributing trough in substantially vertical position.

In testimony whereof I affix my signature in the presence of two witnesses.

CHARLES M. RICHARDSON.
